UNITED STATES PATENT OFFICE.

GEORGE THOMAS MARKEY, OF FORT ATKINSON, WISCONSIN, ASSIGNOR TO JAMES MANUFACTURING COMPANY, OF FORT ATKINSON, WISCONSIN.

VENTILATING MECHANISM.

Application filed March 1, 1923. Serial No. 621,990.

To all whom it may concern:

Be it known that I, GEORGE THOMAS MARKEY, a citizen of the United States, residing at Fort Atkinson, county of Jefferson, and State of Wisconsin, have invented new and useful Improvements in Ventilating Mechanism, of which the following is a specification.

This invention relates to improvements in 10 ventilating mechanism.

More particularly this invention relates to ventilating systems which operate upon the principle of air displacement induced by gravity and in which the inlet device is located in the outer wall near the ceiling of a room to be ventilated and the outlet device is located near the floor and communicates with a ventilating stack or chimney. In such systems the incoming air is directed 20 upwardly against the ceiling to disseminate it about the room so that occupants thereof will not have a current of cool air blowing upon them.

Atmospheric conditions are frequently 25 such that a reversal of the air currents take place causing the air to flow down the chimney and out through the inlet of the ventilating device unless means are provided for checking the reversed current.

It is, therefore, the primary object of this 30 invention to provide a check valve of small inertia and of an extremely sensitive and well balanced construction which will be automatically closed or opened by a very 35 light pressure thereon induced by reversals of air currents flowing through a ventilator opening.

Another object of this invention is to provide a stop for the valve which may be manually 40 adjusted to a plurality of positions, whereby the extent to which the valve may open will be determined by the operator, thus controlling the supply of incoming air, while leaving the valve balanced for actuation 45 by minute differences of pressure.

In the drawings:—

Fig. 1 is a sectional side elevation of an 50 inlet ventilating device, showing the valve and the manually operable stop therefor.

Fig. 2 is a perspective view of a modified 55 form of the device with a portion of the wall broken away to show the valve in closed position.

Fig. 3 is a fragmentary end view of the device in section with the valve removed. 55

Fig. 4 is a view of the valve removed from the ventilator.

Like parts are identified by the same reference characters throughout the several views. 60

The outer wall 1 of a room is provided with an opening 2 adjacent the ceiling 3. The opening is provided upon the outer side with a louver 4 and upon its inner side with a ventilating box 5 having insulating material 6 about the interior of its walls 7, top 8, and bottom 9. The box has an opening 10 communicating with opening 2 in the wall and an opening 11 communicating with the room and adapted to direct the incoming air upwardly against the ceiling 3. 65

The box is provided with a framework of sheet metal adjacent the opening 10, said frame comprising side plates 11' connected together by transverse plate 12 which at one end extends along a portion of the bottom of the box and at the other end rises at an inclination adapted to direct incoming air upwardly. Above plates 11' are disposed triangular shaped plates 13 having inclined sides 14 upon which the valve 15 is adapted to rest in one position to close the opening 10. Spaced from plate 12 and extending transversely between plates 11', is the margin of a valve support 16. The support 16 is 70 formed to provide a flange 17 a portion 17' of which is bent to receive and retain a pintle 19 upon which the valve stop 18 is pivotally mounted. 75

A bracket 20 is secured to the upper face 90 of support 16 and provides a recess transversely of which extends a pin upon which the post 21 is pivotally mounted. Extending at right angles from post 21 is a lever 22 secured thereto and provided with spaced arms 22' adapted to receive post 21 in frictional engagement. Extending transversely between the arms 22' of the lever 22 are pins 23 spaced apart and positioned upon either side of the post to retain the latter properly 100 positioned within the lever. A chain 24 is provided for manually operating the stop about its pivot and passes over a pulley 25 carried by the box. An intermediate portion of the chain is secured to the lever at 105 26, both ends extending through holes 27

in the bottom 9 to a convenient height above the floor of the room, to be reached and utilized to actuate the stop.

Secured to and extending between the plates 12 and 16, are pins 28 and 29 spaced transversely from each other and adapted to support the valve 15. The valve is provided with holes 30 adapted to receive pins 28 and 29 and has a counter balance 31. The valve extends into the cavity formed by the inclined plates 12 and 16 and is of sufficient width to extend across the box and to rest upon the plates 13 in its closed position. The angle of plates 12 and 16 is such as to permit the valve to move freely between its extreme open and closed positions.

In the modified form of the ventilator box shown in Fig. 2, the air is directed downwardly instead of upwardly as in the box shown in Fig. 1, and is disseminated about the room by the platform 32 which is secured to the box by legs 33.

When the ventilating device is delivering air to the room, the air enters openings 2 and 10, holding the valve in open position against the stop 18 and passing over the top of the valve and out through the opening communicating with the room. If a reversal of the air current takes place, so that the air tends to flow from the room into the box and out through openings 10 and 2, the delicately balanced valve will automatically be actuated to closed position by a very slight pressure of the current and opened again when the air tends again to take its normal course into the room.

The stop 18 and its associated mechanism has been provided for the purpose of limiting the extent to which the valve may open, thereby regulating the amount of air that may enter a room. If it is desired to decrease the supply of air, the end 34 of the chain will be pulled downwardly to raise the lever 22 which will rotate the stop 18 about its pivot in a counter-clockwise direction to any desired position. The stop will be retained in any one of a plurality of positions by the post 21 with which the lever is frictionally engaged. When a greater supply of air is desired the stop will be rotated about its pivot in a clockwise direction to any desired position by pulling the end 35 of the chain downwardly. The stop is movable to a position such that the valve may be maintained in a wholly closed position if desired.

A ventilator mechanism has therefore been designed in which an automatically operated valve made of a thin sheet of metal, is so balanced that very slight pressure upon either side will move the valve to closed or open position accordingly. The valve is fulcrumed upon horizontal pins and is for that reason substantially free of all friction that might tend to retard its move-

ments. The fulcrumed mounting of the valve provides a rolling bearing, whereas if a pintle mounting were provided, the valve would have a sliding bearing and would develop considerable friction.

Furthermore, the valve has been provided with means for controlling the extent to which it may open, which means are unsecured to the valve and in no way interfere with sensitiveness of the valve to air pressure. In other words the inertia of the valve is extremely low for the reason that the controlling means are secured to a member which does not move with the valve and is not connected therewith.

I claim:—

1. In a device of the character described, a valve stop comprising a pivoted member having a laterally projecting arm including a pair of friction applying members spaced substantially in the direction of the axis upon which said member is pivoted, and a rod fixed against movement about said axis and projecting between said friction applying elements, said rod being frictionally engaged by said elements, whereby to maintain said arm and member in a selected position of oscillation about said axis.

2. A ventilator adapted for distant control comprising the combination with a ported casing, of a balanced valve adapted in one position to close said port, means for pivotally supporting said valve for free oscillation to and from its closed position, an adjustable stop in the path of oscillation of said valve, means interacting frictionally with said stop and adapted to maintain it in selected positions, and flexible tension motion transmitting connections for the stop, said stop being confined against material lateral movement and bound impositively solely by friction in selected positions of adjustment, whereby it is at all times subject to manipulation through said connections.

3. In a device of the character described, the combination with an oscillatory plate valve, of a stop therefor, including a member pivoted substantially co-axially with said valve and provided with laterally projecting friction arms spaced substantially in the direction of said axis, a rod fulcrumed beneath said axis and projecting between said arms in frictional contact therewith, and means connecting said arms upon either side of said rod, and adapted to maintain said rod in a given relative position longitudinally of said arms.

4. The combination with a passaged ventilator casing provided with a valve seat, of a valve support including means for closing the portion of said casing beneath said seat, a plate valve fulcrumed upon said support and counter balanced beneath its fulcrum, said valve being oscillatable to and from said seat, a valve stop pivoted upon

5 said support and adjustable about its pivot to limit the opening movement of said valve, an arm projecting from said stop, and means connected with said arm and extending to the exterior of said casing, whereby said stop is manually operable.

10 5. The combination with a passaged ventilator casing provided with a valve seat, of a valve support including means for closing the portion of said casing beneath said seat, a plate valve fulcrumed upon said support and counter balanced beneath its fulcrum, said valve being oscillatable to and from said seat, a valve stop pivoted upon 15 said support and adjustable about its pivot to limit the opening movement of said valve, an arm projecting from said stop, a chain guided for movement through said casing and connected intermediate its ends with 20 said arm, and means frictionally associated with said arm for maintaining it in a given adjustment.

25 6. A ventilator including a casing having a passage therethrough and a valve seat therein, a balanced valve oscillatable to and from said seat, a valve stop oscillatable upon an axis nearly co-incident with the axis upon which said valve oscillates, an arm comprising a pair of spaced members projecting from the face of said stop, a post pivoted at one end and extending between said members in frictional relation therewith, and means exterior to said casing for the manual 30 operation of said stop, said arm and post being adapted to maintain said stop in adjustment.

35 7. A ventilator including a casing having a passage therethrough, a pair of upwardly converging plates disposed in the lower part 40 of said passage, the upper margins of said plates being in closely spaced relation, a pin extending horizontally from plate to plate immediately adjacent their upper spaced margins and a valve fulcrumed upon said 45 pin.

8. The combination with a ventilator casing provided with a passage therethrough,

of a valve support in said passage comprising a pair of converging plates having margins in closely spaced relation, valve 50 supporting elements extending between said plates and connected with each, and a valve fulcrumed on said elements and provided below said fulcrum with a counter-weight 55 movable between said plates.

9. The combination with a ventilating device comprising a box-like structure provided with a substantially rectangular air inlet and outlet, of a substantially rectangular valve plate having a weighted end and provided with a plurality of holes adjacent said weighted end, a plurality of pins secured to said structure below the lower margin of the inlet and received through the holes in said valve plate, whereby said plate may have a 60 certain portion of its weight supported above said pins and a substantially equal portion of its weight supported below said pins.

10. The combination with a compartment 70 to be ventilated, said compartment being provided with an opening in a wall thereof, of a casing providing a passage in communication with said opening and in communication at its other end with the outer air, a 75 baffle of substantially the size of said opening spaced from said wall, a valve seat within said casing, a rectangular valve plate provided with a plurality of apertures, substantially horizontal pins passing through 80 said apertures in supporting relation to said plate, whereby said plate is pivoted for oscillation about a horizontal axis to and from said seat, means for counter balancing said 85 valve plate, whereby it is rendered free to move responsive and comparatively light air currents, and a manually adjustable stop adapted to limit the opening movement of said valve plate, whereby the amount of air entering through said casing may be 90 regulated, such air being diffused within said compartment by said baffle.

GEORGE THOMAS MARKEY.
